UNITED STATES PATENT OFFICE.

BEN SIMMONS, OF LARKINS, FLORIDA, ASSIGNOR OF ONE-HALF TO MATTHEW HAMOND,
OF LARKINS, FLORIDA.

ROLLING SCREEN.

1,323,499.

Specification of Letters Patent.

Patented Dec. 2, 1919.

Application filed April 24, 1918. Serial No. 230,481.

To all whom it may concern:

Be it known that I, BEN SIMMONS, a citizen of the United States, residing at Larkins, in the county of Dade and State of Florida, have invented new and useful Improvements in Rolling Screens, of which the following is a specification.

As a rolling screen, the invention is designed to provide a device of this character 10 adapted for attachment on either the inside or outside of a window frame, a particular feature of the invention residing in its simplicity of construction, effectiveness in operation and cheapness of manufacture. 15 The invention is further designed to provide a rolling screen, the rolling member of which is carried in a suitable housing, the screen being capable of being withdrawn from the rolling member, so as to shield a 20 window opening with which the device is used.

A further purpose of the invention resides in a novel construction of guides engaging the side edges of the screen when 25 the latter is withdrawn from its roller, the guides themselves being provided with appropriate notches for engagement by resilient latch members carried by the screen itself, whereby the screen may be held in 30 full extended position or in a position where it is only partially extended.

Still further and other purposes of the invention will appear in the following detailed description.

To the exact construction in which it is shown and described, the invention is not 35 to be restricted. The right is reserved to make such changes or alterations as the actual reduction to practice may suggest, in 40 so far as such changes or alterations are comprehended in spirit by the annexed claim.

In the accompanying drawings:

Figure 1 is a view in front elevation, 45 showing the practical application of the invention, certain parts of the figure being broken away,

Fig. 2 is a vertical sectional view of the structure of Fig. 1,

Fig. 3 is a section on the line 3-3 of Fig. 1,

Fig. 4 is an enlarged detail sectional view showing one of the guides in cross section.

Referring to the drawings, there is shown 50 a window frame A on which the improved

rolling screen B is mounted, the window comprising the vertical stiles 1, the sill 2 and the sash 3.

The screen is composed of a cylindrical housing 4 which is closed at either end, and which is provided at these closed ends with feet 5 by means of which the housing may be supported on the vertical stiles 1 through the medium of appropriate screws which pass through body holes in the feet and thread into the stiles 1. Interior to the housing 4, there is supported a spring actuated roller 6 which simulates the conventional shade roller, the roller 6 being supported in the housing in such a way as to 60 permit its being operated in the same way as is the conventional shade roller. The roller 6 carries the wire fabric (or cloth fabric whichever it may be) 7, which fabric is appropriately attached to the roller 65 by any acceptable means of attachment. It is designed to be rolled onto and off of the roller 6, so that it may be made to shield the window opening when desired or removed from such shielding position when 70 so desired.

The housing 4 is provided with a longitudinal opening 8 through which the screen passes when being rolled onto or off of the roller.

The lower edge of the screen 7 carries a transversely disposed bar 9, which acts as a finish for the lower edge of the screen, and which in addition to this operates as a support for the latch members 10, these 90 two latch members 10 being slidably held on the bar 9 by means of strap members 11. The two latch members 10 are united by means of a U-shaped member 12, which is centrally positioned between the two inner 95 strap members 11. This U-shaped member 12 is made an integral part of the latch members, and its formation into the shape of a U provides enough resiliency to keep the latch members pressed toward the vertical stiles of the window frame, the movement of these two latch members toward the said stiles being limited by stop pins 13 which abut the side edges of the two inner 100 strap members 11.

To protect the screen 7 at its side edges and to aid it in effectively shielding the window opening, there are provided guide members 14 which are channel shape in cross section, and which are provided with the later- 110

ally extending flanges 15 which stand flush with the web portions of the channels. The guides are attached to the vertical stiles 1 by means of appropriate screws which pass 5 through their flanges 15 and thread into the vertical stiles, the two guides being positioned on the window frame so that the legs of the two channels face each other.

On one leg or flange of the channel, each 10 guide is provided with the notches or recesses 16, there being one of these recesses in each guide adjacent to the sill 2. These lateral recesses are designed for engagement by the latch members 10, the ends of which are 15 Z-shape to permit the free ends 17 of the Z's to overlap those flanges of the channels in which the notches are formed. Since the screen 7 passes between the legs or flanges of the guides, the bar 9 which is attached to the 20 lower end of the screen also slidably engages between these legs. Thus the overlapping free ends 17 of the latch members serve to keep the bar 9 nearest that flange in which the notches 16 are formed, thereby keeping 25 the screen 7 from damaging frictional engagement with the remaining flange, since otherwise the bar 9 would tend to cause the screen where it connects with the bar to rub against said remaining flange.

It is obvious that the latch members 10 30 may be disengaged from the recesses 16 by the application of a pressure on the U-shaped member 12 to force the two legs of the latter together. The roller 6 thereafter 35 will operate to raise the screen.

The notches 16 positioned above the lowermost notches 16 provide a means for securing the screen in a partially extended position, such as would be desirable were it nec-

essary to raise the screen for the purpose of 40 passing some object through the window.

From the foregoing description and the accompanying drawings, it is thought that the construction and operation of the invention has been set forth clearly enough to render further description unnecessary.

The invention having been described, what is claimed as new and useful is:

In a device of the kind described, a spring actuated roller, means for operatively mounting the same on a window frame, a window shielding element carried on the said roller and adapted to be wound thereon or unwound therefrom, channel-shaped guides provided with means for attachment to the vertical stiles of a window frame, the said guide receiving the side edges of the said element between their flanges, one flange of each guide being provided with a plurality of notches one of which is positioned adjacent the window frame, a bar attached to the lower end of said window shielding element and having its ends engaged between the flanges of said guides, straps secured to said bar, and latch members slidably mounted in said straps, the latch members being united at their adjacent ends by a U-shaped member which is made an integral part of them, the U-shaped member being resilient and tending to force the latch members in opposite direction so that their opposite ends may engage in the notches on the flanges of the guide, whereby the window shielding element may be positively held in extended position, or shifted to a position of partial closure by pressing on opposite sides of the U-shaped member to force its legs toward each other and thereby withdraw the latch member from engagement in said notches.

In testimony whereof I affix my signature.
BEN SIMMONS.
